UNITED STATES PATENT OFFICE

112,474

DESIGN FOR A CATHODE RAY TUBE OR SIMILAR ARTICLE

Robert M. Bowie, Emporium, Pa.

Application July 9, 1936, Serial No. 63,720

Term of patent 14 years

To all whom it may concern:

Be it known that I, Robert M. Bowie, a citizen of the United States of America, and residing at Emporium, in the county of Cameron and State of Pennsylvania, have invented a new, original, and ornamental Design for a Cathode Ray Tube or Similar Article, of which the following is a specification, reference being had to the accompanying drawing, forming a part thereof, in which the figure is a perspective view of a cath-

ode ray tube or similar article showing my new design, the cross-lined frusto-conical portion being of opaque sheet metal and being substantially rectangular in cross-section throughout the greater part of its length.

What I claim is:

The ornamental design for a cathode ray tube or similar article, substantially as shown and described.

ROBERT M. BOWIE.
